SEPARATION OF HYDROCARBONS

John B. Baird and Nelson C. Turner, Houston,
Tex., assignors to Hudson Engineering Corporation,
Houston, Tex., a corporation of Texas

Application October 27, 1949, Serial No. 123,882

3 Claims. (Cl. 196—8)

1

This invention relates to improvements in absorption separation methods of recovering selected heavy constituents from a mixture of hydrocarbon paraffins and refers more particularly to the fractionation of the overhead product from the rectification still of such installations to substantially denude this product of all but acceptable traces of the less valuable lighted hydrocarbon material.

The normally available mixtures of paraffin hydrocarbons, as for example natural gas, usually contain many constituents ranging in molecular weight from methane to nonane and even heavier. The heavier ones of these hydrocarbons are more valuable than the lighter constituents and therefore, it is the present day practice to separate the lighter hydrocarbon materials from the heavier ones. In some installations the ethane and heavier hydrocarbons are desired, and in other installations propane and higher molecular weight hydrocarbons are desired. Usually traces of the light hydrocarbons in the order of about 5% of the lightest of the heavier hydrocarbons are commercially acceptable. The terms paraffin or any particular paraffin when used herein are intended to include the straight chain and isomers, and also the invention is equally applicable to their corresponding olefins.

It has heretofore been the practice to substantially separate the desirable heavier hydrocarbon constituents of the gases from the lighter material by absorption methods and then to remove all but the last traces of the lighter constituents or constituent by fractionation. In such fractionation processes, it has been the practice to cool and condense at least a portion of the overhead product from the fractionator and return it to the upper portion of the fractionator column as a liquid reflux. The apparatus required to effect this circulation of reflux liquid has a high initial cost and is expensive to operate.

In most of the high pressure absorption installations in present day operation, a liquid product is removed from the feed stock by retrograde condensation that is very rich in the heavier paraffins but which does contain small but objectionable amounts of the lighter hydrocarbons. It has been proposed to contact this liquid with the product recovered from the rich oil to further reduce the light paraffin content of both these materials and this has produced desirable results but has not been effective to denude the liquid product of the undesirable light material to the extent that further demethanization or

2

deethanization is not required.

An object of this invention is to provide an economical method of separating the desirable heavy hydrocarbon paraffins from a mixture of hydrocarbon paraffins containing both light and heavy constituents to produce a product that is sufficiently free of the light material that the product need not be further deethanized or demethanized as the case may be.

10 Another object is to provide an economical method of fractionating a mixture of hydrocarbon paraffins of predominately selected heavy constituents to sufficiently free it of the light paraffins that the product need not be further deethanized or demethanized as the case may be.

15 A further object is to provide in a method of separating selected heavy hydrocarbons from a mixture of hydrocarbon paraffins, of the absorption class, a method of fractionating the overhead product from the still for rectifying the rich oil wherein the condensate from the gas feed stream is employed as a reflux liquid to substantially denude both the reflux liquid and the still product of the lighter hydrocarbons.

20 25 Still another object is to provide in a method of separating selected heavy hydrocarbons from a mixture of hydrocarbon paraffins, of the absorption class, a method of fractionating the overhead product from the still for rectifying the rich oil wherein the retrograde condensation product

30 35 from the gas feed stream is employed as a reflux liquid to substantially denude both the reflux liquid and the still product of the lighter hydrocarbon material, and wherein the overhead product from the fractionator is recycled to the absorption process where any escaping desirable heavy hydrocarbons may be stripped therefrom.

40 45 A still further object is to provide a method of substantially denuding the overhead still product from an absorption separation installation of the less valuable light hydrocarbon material in a fractionator column wherein a condensate obtained from the feed gas stream is employed as a reflux liquid and is itself denuded of its content of light constituents.

Other and further objects of this invention will appear from the following description.

In the accompanying drawings which constitute a part of the instant specification and are to 50 be read in conjunction therewith, the single figure is a schematic flow diagram illustrating an absorption separation installation constituting an embodiment of this invention.

This invention, in general, is concerned with 55 the portion of an absorption separation process

wherein the overhead product from the rectifier for the rich oil and the retrograde condensation product from the feed gas stream is denuded of the less valuable light hydrocarbon material. For this reason, in the interest of simplicity, the absorption process and rectification step thereof have been simply and schematically shown in the drawings, but it is contemplated that the improvement of this invention may be employed in connection with any conventional absorption separation method and installation wherein, for instance, a plurality of absorption vessels such as an absorber and reabsorber may be employed and wherein the condensate separated from the feed gas stream may be enriched by flashing into several successive reduced pressure stages before it is employed as the reflux liquid in accordance with the improvement of this invention. All of such methods and equipment are well known and understood by those skilled in the art.

Referring to the drawings, the numeral 1 designates an absorber vessel which may be of the usual bubble tray type, the rectifier still for the rich oil from the absorber is shown at 2, and the fractionator tower from which the final product free from the lighter material is obtained is shown at 3. The feed stream for the process may be obtained from any of the usual sources and is introduced to the installation through conduit 4. Vessel 5 provides an accumulator for the condensation product which is obtained from the feed stream either by the reduction of pressure in the case of a high pressure gas or the increase in pressure in the case of a low pressure gas, and in some instances, the feed gas for a single installation may be from both high and low pressure sources. The condensate is withdrawn from vessel 5 through conduit 6 and this line may be controlled by the float control valve 7. This condensate is conducted by conduit 6 to the fractionator 3 where it will provide the reflux liquid for the fractionation step in a manner to be hereinafter more fully described.

The uncondensed portion of the feed gas stream is conducted from vessel 5 to absorber 1 through conduit 8 and enters below the trays of the absorber. The absorption step may be of the conventional type with the lean oil introduced into the upper portion of the absorber through conduit 9 and may be constituted of any desirable absorbent menstruum. The lean oil and rising gases pass in countercurrent flow within the absorber and the selected heavier hydrocarbon constituents are dissolved from the uprising gas by the downcoming absorbent medium. The undissolved gases pass from the absorber through conduit 10 and may be disposed of in any conventional manner. The rich absorbent menstruum, containing the heavy hydrocarbons from the feed stream, is withdrawn from the bottom of the absorber through conduit 11 and is conducted to a midpoint of rectifier 2. Heat is supplied to the lower portion of the rectifier as by a steam connection 12.

In the rectifier, the rich oil is separated into the dissolved hydrocarbons which pass through conduit 13 as an overhead product and the rectified absorbent menstruum or lean oil, the latter being withdrawn from the lower portion of the rectifier through line 9. This lean oil is circulated by pump 14, together with any lean oil from a reservoir which enters line 9 through conduit 15 and is recirculated through the absorber. The still is shown schematically with the reflux cir-

culating apparatus omitted in the interest of simplicity.

The overhead still product passes through line 13, cooler 16 and condenser 17 into the fractionator 3. In the cooler and condenser, the stream is partially condensed and water is separated therefrom through trap 17a and may be withdrawn through line 18 controlled by a suitable float valve.

10 The partially condensed overhead still product enters the fractionator and the liquid portion flows downwardly therein while the gaseous portion rises upwardly in contact with the liquid reflux in the form of the condensate from vessel 5. In this gas and liquid contact, the selected heavy constituents of the upcoming gas are dissolved by the downcoming liquid and replace the light constituents therefrom. The undissolved light constituents pass as an overhead product through conduit 19 and are circulated by compressor 20 to the lower portion of the absorber in order that the undissolved selected heavy hydrocarbons escaping therewith may be recovered.

20 In order to completely denude the overhead still product and the condensate of the light hydrocarbon material, it is necessary to introduce heat into the fractionator at the lower portion in the form of a reboiler. It has been found that 25 relatively low pressures may be employed within the fractionator and pressures ranging between 100 p. s. i. and 150 p. s. i. are recommended for this purpose. With such low pressures, a low level heat may be employed and desirably a steam coil 23 employing exhaust steam from the plant 30 is utilized for this purpose. It is usually desirable to employ a tower inter-cooler to off-set the rise in temperature of the downcoming liquid due to the absorbed heat of vaporization. Any suitable inter-cooler may be employed for this purpose but it is preferred to utilize a liquid trap shown at 3a within the fractionator. This liquid trap permits the escape of rising gases thereby but collects the downcoming liquid which is then 35 circulated through cooler 21 by pump 22 and introduced into the tower just below trap 3a. By this combination of the application of the heat to the bottom product within the fractionator and the cooling of the downcoming liquid within the fractionator, a proper balance may be maintained within the fractionator so as to completely 40 denude the two hydrocarbon streams entering the fractionator of undesirable light constituents to the extent that additional steps and apparatus for their removal are not required.

45 55 This reflux condensate is readily available in rather large quantities in most plants and its constituency and low temperature are such that it lends itself extremely well for use as a reflux liquid from a foreign source in the fractionator. 60 In accordance with this invention, this condensate is employed to reduce the cost of initial equipment and also the cost of operating the fractionator for freeing the selected heavy hydrocarbons from the lighter material adding in 65 this fashion materially to the efficiency of the operation. In addition, it has heretofore been necessary to further treat this condensate to remove the lighter material therefrom and this is accomplished simultaneously with the de-methanization or deethanization of the still overhead product, thus adding materially to the efficiency of the process.

The bottom product of the fractionator, which is free of the less valuable lighter materials, are 70 withdrawn from the fractionator through line 75

24 and may either be utilized in this form or further separated into its various constituents in the manner well known to those skilled in the art.

The method of this invention lends itself particularly for use in continuous operations. A continuous feed stream with its pressure adjusted approximately to that desired within absorber 1 enters the system through conduit 5 and the condensate is separated from the feed stream in vessel 5 to be withdrawn through conduit 6. The uncondensed portion of the feed stream enters the absorber and passes upwardly therein in gas to liquid contact with the downcoming lean oil or absorbent menstruum. This absorption process, as heretofore indicated, may be of any conventional character and may include a plurality of these towers. The residue gas passes from the absorber system through conduit 10 and the rich absorbent menstruum is conducted through pipe 11 to a suitable rectifier still where it is caused to give up its dissolved hydrocarbon constituents due to the action of the stripping steam from connection 12. The lean oil from the bottom of the rectifier may be recirculated in the absorption system through conduit 9 and a proper quantity of oil may be kept in the system by introducing fresh oil as needed through conduit 15 from a suitable lean oil reservoir not shown in the drawings.

The hydrocarbons that have been dissolved by the absorbent menstruum in the absorber are released in the rectifier and pass as an overhead product through conduit 13, cooler 16 and condenser 17 into the fractionator. These hydrocarbon constituents are predominantly the desired heavy constituents but do contain an appreciable quantity of the lighter material. This material is advantageously and economically separated from the heavier constituents in fractionator 3 and at the same time, the condensate from vessel 5 is reconstituted or denuded of its lighter constituents within acceptable commercial limits.

As heretofore indicated, the condensate from vessel 5 may, if desired, be flashed through successive pressure reduction stages to approximately the pressure prevailing within the fractionator 3. The vapors given off during such flashing operations may be introduced into the absorption system in order to recover the heavy constituents thereof. This condensate is usually available in rather substantial quantities and must be subjected to some treatment to denude it of its lighter constituents. The condensate is obtained in a cold state and is advantageously employed as the reflux liquid being introduced into the fractionator through conduit 6. In passing downwardly through the column, the reflux liquid is brought into intimate gas and liquid contact with the upgoing vapors in the fractionator. These vapors originate from the uncondensed portion of the rectifier overhead product and also from the release of vapors by the heater 23 which is effective to boil out all but acceptable traces of the lighter hydrocarbon material to be eliminated.

In order to effect a proper balance within the fractionator, it is usually necessary to cool the downgoing liquid in what is generally referred to as a tower inter-cooler. The proper balance between the quantity of reflux liquid, the cooling in the inter-cooler, and the amount of reboiling due to heater 23 is effective to free the bottom prod-

uct of the fractionator tower of all but acceptable traces of its lighter constituents.

The overhead product from fractionator 3 will be composed primarily and predominantly of the lighter materials removed from the rectifier overhead product and the condensate. However, this product, leaving the fractionator through line 19, will contain some heavier hydrocarbons and in order to recover these, it is often desirable to introduce this stream of gas into absorber 1 near its bottom where it will pass upwardly in countercurrent relation with the downcoming absorbent menstruum.

In the fractionation of the rectifier overhead product in the conventional manner, it is necessary to operate the fractionator at rather elevated pressures such as, for example, in the neighborhood of 550 p. s. i. The overhead product from the fractionator is cooled and partially 20 condensed to provide a reflux liquid which is then circulated back into the fractionator near its top. In accordance with this invention, the rectifier still overhead product may be fractionated at much lower pressures, as, for example, 135 25 p. s. i. is preferred, and in the same operation, the retrograde condensation product from the feed stream of gas is de-methanized or de-ethanized, as the case may be. This low pressure operation avoids the necessity of operating the fractionator reboiler in the region of the critical temperature 30 of the product.

From the foregoing it will be seen that this invention is one well adapted to attain all of the ends and objects hereinabove set forth, together 35 with other advantages which are obvious and which are inherent to the method.

It will be understood that certain features and subcombinations are of utility and may be employed without reference to other features and 40 subcombinations. This is contemplated by and is within the scope of the claims.

As many possible embodiments may be made of the invention without departing from the scope thereof, it is to be understood that all matter herein set forth or shown in the accompanying drawings is to be interpreted as illustrative and not in a limiting sense.

The invention having been described, what is claimed is:

1. A process for fractionating a natural gas feed containing methane and hydrocarbons heavier than methane to recover said heavier hydrocarbons substantially free, within acceptable limits, from said methane which comprises the steps of condensing a portion of said feed to obtain a condensate comprising a portion of said heavier hydrocarbons admixed with methane in an undesirably high concentration, contacting the remainder of said feed with absorption oil in an absorption zone to produce an absorption oil enriched with heavier hydrocarbons and methane from said remainder of said feed, passing said enriched oil to a rectifier and stripping it therein to produce a rectifier bottoms product comprising lean absorption oil and a rectifier overhead product comprising methane and at least a portion of said heavier hydrocarbons contained in said enriched oil, said methane being present in an undesirably high concentration in said rectifier overhead product, returning said lean absorption oil to said absorption zone, feeding said rectifier overhead product to a fractional distillation column, adding heat to said column at a point below the introduction of said rectifier overhead product thereinto, refluxing said col-

suming solely with said condensate introduced therewith at a point above which said rectifier overhead product is introduced therewith, removing as an overhead product from said column a mixture composed predominantly of methane from said condensate and methane from said rectifier overhead product, and recovering as a bottom product from said column a mixture of said heavier hydrocarbons from said condensate and from said rectifier overhead product free, within acceptable limits, from said undesirable methane, said column having sufficient of said heat added thereto to strip said bottom product of the undesirable methane.

2. A process for fractionating a natural gas feed containing ethane, methane and hydrocarbons heavier than ethane to recover said heavier hydrocarbons substantially free, within acceptable limits, from said ethane and methane which comprises the steps of condensing a portion of said feed to obtain a condensate comprising a portion of said heavier hydrocarbons admixed with ethane and methane in an undesirably high concentration, contacting the remainder of said feed with absorption oil in an absorption zone to produce an absorption oil enriched with heavier hydrocarbons and ethane and methane from said remainder of said feed, passing said enriched oil to a rectifier and stripping it therein to produce a rectifier bottoms product comprising lean absorption oil and a rectifier overhead product comprising ethane and methane and at least a portion of said heavier hydrocarbons contained in said enriched oil, said ethane and methane being present in an undesirably high concentration in said rectifier overhead product, returning said lean absorption oil to said absorption zone, feeding said rectifier overhead product to

a fractional distillation column, adding heat to said column at a point below the introduction of said rectifier overhead product therewith, refluxing said column solely with said condensate introduced therewith at a point above which said rectifier overhead product is introduced therewith, removing as an overhead product from said column a mixture composed predominantly of ethane and methane from said condensate and ethane and methane from said rectifier overhead product, and recovering as a bottom product from said column a mixture of said heavier hydrocarbons from said condensate and from said rectifier overhead product free, within acceptable limits, from said undesirable ethane and methane, said column having sufficient of said heat added thereto to strip said bottom product of the undesirable ethane and methane.

3. The process of claim 2 wherein said fractional distillation column is maintained at a pressure within the range of 100 to 150 pounds per square inch.

JOHN E. BAIRD,
NELSON C. TURNER.
